COMBINATION UNDER GARMENT FOR LADIES.

0. 19,187.

Patented July 2, 1889

Fig. 1.

Fig. 2.

UNITED STATES PATENT OFFICE.

MARGARET VIRGINIA BOTTS, OF PHILADELPHIA, PENNSYLVANIA.

DESIGN FOR A COMBINATION UNDER-GARMENT FOR LADIES.

SPECIFICATION forming part of Design No. 19,187, dated July 2, 1889.

Application filed June 3, 1889. Serial No. 312,990. Term of patent 7 years.

To all whom it may concern:

Be it known that I, MARGARET VIRGINIA BOTTS, of the city and county of Philadelphia, and State of Pennsylvania, have invented and 5 produced a new and original Design for a Combination Under-Garment for Ladies; and I do hereby declare that the photographic prints accompanying this specification convey to any one a clear understanding of how 10 the said combination under-garment for ladies, when made up by my design, will appear.

Figure 1 represents the front view of said combination under-garment for ladies. Fig. 2 represents the back view of the same.

15 The design comprises a combination under-garment for ladies, consisting of a shirt and drawers, the shirt portion having its upper outline substantially horizontal, being in this respect similar to the upper outline of a cor-

set—that is to say, it is without armhole- 20 openings. It is, moreover, without front or back openings, while the design for the drawers portion shows the garment open from the short leg portion up to the waist-line both front and back, the entire garment in other 25 respects outlining the human figure.

My design is represented in the accompanying illustrations as having shoulder-straps.

What I claim as my invention, and desire to secure by Letters Patent, is— 30

The design for a combination under-garment for ladies, as herein described, and shown in the accompanying photographic prints.

MARGARET VIRGINIA BOTTS.
